UNITED STATES PATENT OFFICE.

JOHN D. PEDERSEN, OF JACKSON, WYOMING.

RIFLE-BARREL.

1,355,421.

Specification of Letters Patent. Patented Oct. 12, 1920.

Application filed June 27, 1917, Serial No. 177,252. Renewed January 29, 1920. Serial No. 354,883.

To all whom it may concern:

Be it known that I, JOHN D. PEDERSEN, a citizen of the United States, residing in Jackson, in the county of Lincoln and State 5 of Wyoming, have invented certain new and useful Improvements in Rifle-Barrels, of which the following is a specification.

A principal object of this invention is to furnish an improved barrel especially adapted for use in rifled shoulder arms. A further object is to provide means whereby the work of finally shaping the projectile to conform to and engage with the rifling ribs and in the rifling grooves, will be accomplished by and in successive stages or periods, so that said work will be carried out in the rearward portion of the barrel in a modulated and progressive manner. Further advantages and objects are pointed out 15 and explained in the course of the following description.

In the drawings accompanying and forming a part of this specification, Figure 1 is a side view, principally in section, of a rifle barrel made in accordance with my present improvements, and of composite construction; and, Fig. 1^a is a similar view drawn 25 on a different scale, of the barrel when made of integral construction.

Fig. 2 is an end view, as seen from the left-hand in Fig. 1.

Figs. 3 and 4 are cross sections in lines X³ and X⁴, respectively, of Fig. 1, and Figs. 3^a and 4^a are views supplemental thereto as 35 hereinafter explained.

Figs. 5, 6 and 7 are enlarged detail views which are especially arranged for illustrating certain features of the rifling, as herein-after more fully explained.

Figs. 5^a and 5^b are views analogous to a portion of Fig. 5, for illustrating certain variations in the form or arrangement of successive portions of the rifling ribs.

Fig. 6^a is a view similar to Fig. 6, for illustrating a further modification of, or variation in, the rifling of the barrel.

Fig. 8 is a diagrammatic view for approximately representing certain features of my improved rifle barrel with relation to the 50 usual gas-pressure curve or diagram.

Similar reference characters designate like parts in all the views.

Referring to the drawings, B indicates a rifle barrel of ordinary character; it may 55 have, in practice, any suitable external size and form, and in Fig. 1, also in Fig. 1^a, a

large portion of the length is broken away, and only the rearward portion of the barrel B,—which, for the purposes of this description, I designate as the main barrel,—may have such size, length and proportions as may be suitable for the particular firearm of which this barrel is to form a part, and I have herein represented in an approximate manner such a barrel of the class common to military shoulder arms. These barrels are now generally made with bore,—as E, Fig. 1,—having a diameter of about three-tenths of one inch, but in the present drawings, Figs. 1 to 5^b, are drawn on a somewhat larger scale.

At the rearward end thereof, the barrel B (Figs. 1, 2) is shown at 10, reduced in size and threaded, by way of showing one ordinary way,—which may be adopted when desired,—of fitting the barrel to be removably fixed in the usual receiver, or frame, (not shown) of a firearm, in a well-known manner. Also, said main barrel B is shown 80 as being bored out, (to the lines 12, 12, Fig. 1), to form the usual cartridge chamber, as 12, for the shell, or “powder-case,” (not shown) of a high-power cartridge having a long-range projectile. Into said chamber 12, a secondary barrel, D, is closely fitted, thus forming a complete barrel having a composite construction. It should be understood, however, that in some instances, if desired, the portion D may be made integral 90 with the portion B; in this case, of course, the barrel B will have no chamber 12 available for use on the removal of the member D. This integral form of the complete barrel is illustrated in Figs. 1^a and 8, and is 95 hereinafter more fully explained.

In the composite form of the barrel shown in Figs. 1, 2, 3, the member D is extended rearwardly of the member B, and is there shown enlarged, as at 14, and provided with 100 a cartridge chamber 15 the forward portion of which is an un-rifled projectile seat; this chamber should be suitable for the cartridges which, in any given instance, are to be used in the composite barrel. Said chamber 15, in some instances if desired, may be of the same size and proportions as the chamber 12, but said composite form of the barrel is more especially intended for use with ammunition of two kinds, viz., for 105 high-power, long-range cartridges when the member D is removed, and for a lower

power and shorter range cartridge, when said member D is in place.

Thus in the complete barrel, this has a continuous bore which in a short length 5 thereof, and adjacent to the chamber 15 in the rear end thereof, (as in the zone N from line V to line V', Figs. 1, 1^a, 8), is provided with relatively small rifling ribs for initially grooving a projectile, and which forward 10 of said small ribs; and forward of said zone N of the initial projectile-grooving action, is provided with rifling ribs arranged for increasing the initial grooving of the projectile. Thus the complete barrel-rifling 15 operates to groove the projectile by a two-stage method or process, whereby the initially-grooved projectile is subsequently re-grooved or rifled by an operation which begins after a time-interval that is subsequent 20 to the completion of said first operation. A further feature is that said zone N of initial grooving, is extended forwardly from said chamber 15 to a length or point forward of the position when the gases normally will 25 have reached their maximum pressure, so that the projectile will pass from the relatively small to the larger rifling ribs at a time when the gas-pressure is beginning to decrease; during this period,—or “time-interval,”—it is believed that the velocity of 30 the projectile will be most rapidly increasing, not in ratio or percentage of speed, but as regards the distance traveled through in a given unit of time; this kind of increase 35 of velocity must, of course, disappear at or somewhat before the projectile leaves the muzzle of the barrel.

The main barrel B is shown provided with rifling ribs, 5, (preferably of a usual helical form), which are indicated of a conventional form, in the sections, in Figs. 4 and 5. Similarly, the secondary or auxiliary barrel-portion D', is shown provided with the smaller rifling ribs 7, shown in section in 45 Figs. 2, 3, and 5. These two sets of ribs are intended to be of similar number and arrangement, (Fig. 5), and thus form a continuation, the one of the other. This relation of the ribs is illustrated (but without 50 out the curvature thereof) in a plan view, Fig. 6, and in a side view of the ribs in Fig. 7; in these views a further feature is shown, in that, within the zone 8, (see Figs. 1, 1^a, and 6), the portion 5' of the ribs 5 is reduced to a tapering form, thus avoiding 55 a sudden increase in size or a marked obstruction at the forward end of the rib 7. Said additional feature, however, of the tapered parts 5', may not be required in all cases, and it is not essential to the principal features of my present invention.

For convenience of illustration, and to aid clearness in the drawing, the depth of the rifling grooves (that is, the height of the 60 rifling ribs) has been shown somewhat ex-

aggerated, and the ribs, as 7, of the initial rifling are shown of a size relatively large as compared with the ribs, as 5, of the final or main rifling. (Compare Figs. 5, 5^a, 5^b, 6, 7). The relative effects of the ribs upon a 70 projectile are approximately shown in Figs. 3^a and 4^a, which correspond with the inner outlines of the bore of the barrel, in Figs. 3 and 4, respectively. Thus Fig. 3^a shows a cross-section of a projectile, J as if initially 75 grooved,—as at 7^a,—by the ribs 7, Fig. 3. Similarly, Fig. 4^a shows said projectile as having the grooves 7^a enlarged to the form 5^a by the ribs, 5, of the barrel B, in Fig. 4. In the form of barrel shown in Fig. 1, said 80 groove enlargement will take place when the projectile passes the line 9, or within the zone 8.

The slight resistance offered by the relatively small ribs 7 to the initial forward 85 movement of the projectile, permits this movement to begin at a time (at a moment) when the gas-pressure is still comparatively low so that the space behind the projectile will be materially enlarged during a very 90 early stage of the combustion. Consequently, during that initial forward movement, the projectile will have not only a low velocity, but also a low degree of acceleration, so that a minimum amount of power 95 will be consumed during that moment in inaugurating the rotation of the projectile, and thereby permit a more rapid acceleration of the forward movement under a given and relatively low gas-pressure. Thus the 100 rapidly increasing forward movement while the projectile is subjected to the low rib-resistance, tends to correspondingly increase the gas-space before the gas-pressure can rise to its maximum. As a result of this action, the curve by which the gas-pressure is 105 usually represented in a well-known dia-grammatic manner, will be materially modified in a way to show a delay,—as compared with the hitherto accepted practice,—of the 110 moment when the gas will attain maximum pressure; this normally operates to reduce the maximum strain upon the barrel due to the burning therein of a given quantity of powder behind a projectile 115 of a given weight, and also,—with a given limit of that strain,—provides for burning a relatively larger quantity of powder behind a projectile of a given weight. These features and advantages appertain, of 120 course, to the complete barrel whether this is of integral or composite construction.

By reason of the modulation, as above explained, of the forces and pressures, the torsional strain on the initial rifling (and especially during the first one or two inches of said forward movement of the projectile), will be less than normally occurring with the usual style of rifling which is uniform throughout the length of the barrel. Hence 125 130

my present improvements are especially applicable to rifled firearms having barrels of composite construction, and in which a main barrel is adapted for using high-power cartridges and is also, for some uses, provided with "an adapter", the bore of which forms a rearward extension of the bore of the main barrel; one arm of this class,—a military shoulder-arm,—is described in my application filed April 28th, 1917, Serial No. 165,171, to which reference may be had.

In practice, by the time when the projectile has reached the forward end of the initial ribs 7, and thus come to the larger rifling ribs 5, the projectile has acquired such a velocity and momentum that it will "take" the rifling of the main barrel without difficulty, and will do this before the period of the most rapid acceleration. As a result, therefore, of the said features and mode of action, when the barrel is provided with the relatively thin adapter-extension or supplemental barrel, as D', this is so far protected and relieved of the otherwise heavy strain, as to be reliable and effective under the severe conditions of continued service. Thus, also, I avoid the highly destructive action upon the projectile, which occurs when the bore of the adapter-barrel is a smooth-bore (not herein shown); that construction (as I have found by extended trials) allows the projectile to initially advance too rapidly, so that on striking the rifling ribs, as at 9, of the main barrel,—and being then without rotation,—the projectile is impaired in quality and in trajectory, and often will be so cut and deformed as to be practically destroyed before leaving the barrel.

For more fully indicating the foregoing explanations, I have shown in Fig. 8, a gas-pressure diagram, M, drawn in a conventional manner with the base-line *m* thereof along side of the rifle barrel B', this being substantially the same as the composite form of barrel, except that it is shown as if made integral. In this diagram, the pressure curve 3 is of a form representing results such as commonly obtained in military rifles. Beginning at the point, 3^a of initial pressure, the line 3 then rises rapidly to the point, as 3^b, of a maximum pressure which is normal to the barrel. By this term, of course, is meant that the line, as 3^c, to which the projectile will have gone forward, when the projectile is propelled by a charge normally used in the ammunition for the use of which the cartridge chamber 15 is constructed. In practice, this portion of forward movement of the projectile will extend forwardly at least as far as a line of maximum pressure,—as 3^c, Fig. 8,—and preferably should extend at least to said line when the barrel is used for the largest powder charges proper therefor. Thus the small-ribs zone, as N, may usually have a length which is somewhat

greater than that of the rising-pressure zone P, so that,—as herein explained,—the increased resistance due to the projectile encountering the larger ribs 5, will be delayed, and so will not occur until after the gas-pressure has begun to reduce; this feature, or point of action, is indicated in an evident manner by the descending part 3^d of said pressure curve 3. In practice, the minimum length of the zone N may be regarded as equal to two and one-half times the diameter of the bore E, while a normal and preferable range thereof may be between four and ten diameters or calibers, according to size of bore, the twist of the rifling, and the character and power of the cartridges to be used; all these matters or factors are readily ascertainable by trial in any particular instance.

The position where the smaller ribs 7 meet the larger ribs 5, may be designated as the groove-enlarging zone; in Figs. 1, 1^a, and 6, this zone, 8, has a considerable length, so that the fully formed ribs 7 and 5 may be connected by an intervening length, as 5', constituting a groove-enlarging means. Also, said portion 5' may be regarded as constituting a rearward part of one of said larger ribs, as 5, which is tapering and is thus reduced in size to correspond with one 5' of said smaller ribs, as 7, and thereby form a means for enlarging the grooving of the projectile in the gradual manner normally due to the action of a wedge. The form and character of the groove enlargement 100 may vary in different instances; this will be seen by a comparison of Figs. 5, 5^a and 5^b. In Fig. 5^a the initially-grooving rib 7 is of the same width, but of less height, than rib 5 and operates to increase the depth of the grooving; in Fig. 5^b, the rib 7 is of the same height but of less width than rib 5, and operates to increase the width of the grooving; in Fig. 5, the rib 5 is both higher and wider than the rib 7, and hence operates to increase both the depth and width of the grooving. In each said instance, however, it is evident that the barrel, forward of said small rifling ribs, as 7, is provided with larger rifling ribs that are in position for increased the initial grooving of the projectile.

In Figs. 1, 6 and 7,—also in Fig. 1^a,—the ribs 7 are indicated as extending forward to closely join or contact with the larger ribs 5, but it should be understood that in some instances if desired, a space, or un-ribbed zone, as 8', Fig. 6^a, may be located between said ribs. In this case, however, the ribs 7 and 5 not only form a "continuous" rifling rib for the complete barrel, since both said ribs,—as shown in Fig. 6^a,—are in alignment with the same meridian line, S, but said larger ribs 5, similarly and equally as in Fig. 6, are in position forward of said small

ribs, for increasing the initial grooving of the projectile. By its motion and momentum acquired in the zone N, the projectile will readily pass from the ribs 7 and over said zone 8' and continue along the rib 5, in the required manner. The special features here described in connection with Fig. 6^a, have the advantage of permitting the extreme forward part,—as the narrow zone 10 8',—to be without ribs, thus tending to reduce the strain at and on the forward part, or point-portion of the insertible part D', which is contiguous to the line 9.

Having thus described my invention, I 15 claim:

1. A rifle barrel for the two-stage grooving of a projectile, said barrel having in the rear end thereof a cartridge chamber with an unrifled projectile seat, and having a continuous bore which in a zone thereof contiguous to said projectile-seat is provided with relatively small projectile-grooving rifling ribs for initially-grooving a projectile, and which forward of said small ribs 20 is provided with larger rifling ribs that are in position for increasing the initial grooving of the projectile, said bore being of a uniform diameter from said chamber to a point forward of the rearward end of said 25 larger rifling ribs.
2. A rifle barrel for the two-stage grooving of a projectile, said barrel having in the rear end thereof a cartridge chamber with an unrifled projectile seat, and having a continuous bore which adjacent to said projectile-seat is provided with relatively small projectile-grooving rifling ribs for initially-grooving a projectile, and which forward of said small ribs 30 is provided with rifling ribs having groove-widening inclines and of a size and arrangement for increasing the depth of the initial grooving of the projectile, said bore being of a uniform diameter from said chamber to a point forward of the rearward end of said 35 larger rifling ribs.
3. A rifle barrel for the two-stage grooving of a projectile, said barrel having in the rear end thereof a cartridge chamber with an unrifled projectile seat, and having a continuous bore which adjacent to said projectile-seat is provided with relatively small projectile-grooving rifling ribs for initially-grooving a projectile, and which forward of said small ribs 40 is provided with rifling ribs having groove-widening inclines and of a size and arrangement for increasing the depth of the initial grooving of the projectile, said bore being of a uniform diameter from said chamber to a point forward of the rearward end of said 45 larger rifling ribs.

4. A rifle barrel for the two-stage grooving of a projectile, said barrel having in the rear end thereof a cartridge chamber with an unrifled projectile seat, and having a continuous bore which adjacent to said projectile-seat is provided with relatively small projectile-grooving rifling ribs for initially-grooving a projectile, and which forward of said small ribs 50 is provided with larger rifling ribs having groove-widening inclines and of a size and arrangement for increasing the width of the initial grooving of the projectile, said bore being of a uniform diameter from said chamber to a point forward of the rearward end of said 55 larger rifling ribs.
5. A rifle barrel for the two-stage grooving of a projectile, said barrel having in the rear end thereof a cartridge chamber with an unrifled projectile seat, and having a continuous bore which adjacent to said projectile-seat is provided with a series of relatively small projectile-grooving rifling ribs for initially-grooving a projectile, said bore being of a uniform diameter from said chamber to a point forward of the rearward end of said 60 larger rifling ribs, and which forward of said small ribs is provided with a corresponding series of relatively larger parallel-sided rifling ribs that are continuations, respectively, of said smaller ribs.

6. A rifle barrel for the two-stage grooving of a projectile, said barrel having in the rear end thereof a cartridge chamber with an unrifled projectile seat, and having a continuous bore which adjacent to said projectile-seat is provided with relatively small projectile-grooving rifling ribs for initially-grooving a projectile, and which forward of said small ribs 65 is provided with larger rifling ribs each having a rearward portion thereof reduced in size and shaped to form a groove-enlarging means.

7. A rifle barrel for the two-stage grooving of a projectile, said barrel having in the rear end thereof a cartridge chamber with an unrifled projectile seat, and having a continuous bore which in a zone thereof contiguous to said projectile-seat is provided with relatively small projectile-grooving rifling ribs for initially-grooving a projectile, and which forward of said small ribs 70 is provided with larger rifling ribs that are in position for increasing the width of the initial grooving of the projectile, said bore being of a uniform diameter from said chamber to a point forward of the rearward end of said 75 larger rifling ribs.

8. A rifle barrel for the two-stage grooving of a projectile, said barrel having in the rear end thereof a cartridge chamber with an unrifled projectile seat, and having a continuous bore which in a zone thereof contiguous to said projectile-seat is provided with relatively small projectile-grooving rifling ribs for initially-grooving a projectile, and which forward of said small ribs 80 is provided with larger rifling ribs that are in position for increasing the width of the initial grooving of the projectile, said bore being of a uniform diameter from said chamber to a point forward of the rearward end of said 85 larger rifling ribs.

9. A rifle barrel for the two-stage grooving of a projectile, said barrel having in the rear end thereof a cartridge chamber with an unrifled projectile seat, and having a continuous bore which in a zone thereof contiguous to said projectile-seat is provided with relatively small projectile-grooving rifling ribs for initially-grooving a projectile, and which forward of said small ribs 90 is provided with larger rifling ribs that are in position for increasing the width of the initial grooving of the projectile, said bore being of a uniform diameter from said chamber to a point forward of the rearward end of said 95 larger rifling ribs.

10. A rifle barrel for the two-stage grooving of a projectile, said barrel having in the rear end thereof a cartridge chamber with an unrifled projectile seat, and having a continuous bore which adjacent to said projectile-seat is provided with a series of relatively small projectile-grooving rifling ribs for initially-grooving a projectile, said bore being of a uniform diameter from said chamber to a point forward of the rearward end of said 105 larger rifling ribs, and which forward of said small ribs is provided with a corresponding series of relatively larger parallel-sided rifling ribs that are continuations, respectively, of said smaller ribs.

11. A rifle barrel for the two-stage grooving of a projectile, said barrel having in the rear end thereof a cartridge chamber with an unrifled projectile seat, and having a continuous bore which adjacent to said projectile-seat is provided with a series of relatively small projectile-grooving rifling ribs for initially-grooving a projectile, said bore being of a uniform diameter from said chamber to a point forward of the rearward end of said 110 larger rifling ribs, and which forward of said small ribs is provided with a corresponding series of relatively larger parallel-sided rifling ribs that are continuations, respectively, of said smaller ribs.

ing of a projectile, said barrel having in the rear end thereof a cartridge chamber with an unrifled projectile seat, and having a continuous bore which in a zone thereof adjacent to said projectile-seat is provided with a series of relatively small projectile-grooving rifling ribs for initially grooving a projectile, and which forward of said small-ribs zone is provided with a corresponding series of relatively larger parallel-sided rifling ribs that are continuations, respectively, of said smaller ribs, said barrel also having said small-ribs zone of a length extending forwardly of the line of maximum gas-pressure which is normal to the barrel.

9. A rifle barrel for the two-stage grooving of a projectile, said barrel having in the rear end thereof a cartridge chamber with

an unrifled projectile seat, and having a continuous bore which in a zone thereof adjacent to said projectile-seat is provided with a series of relatively small projectile-grooving rifling ribs for initially grooving a projectile, and which forward of said small-ribs zone is provided with a corresponding series of relatively larger parallel-sided rifling ribs for more deeply grooving the projectile, said barrel also having said small-ribs zone extending forwardly at least as far as a line of maximum gas-pressure which is normal to the barrel.
